By his affy. Edm. De Valin

UNITED STATES PATENT OFFICE.

WILLIAM H. DE VALIN, OF SAN RAFAEL, CALIFORNIA.

BRICK-KILN.

SPECIFICATION forming part of Letters Patent No. 300,054, dated June 10, 1884.

Application filed August 17, 1883. (No model.)

To all whom it may concern:

Be it known that I, WILLIAM H. DE VALIN, a citizen of the United States, residing at San Rafael, Marin county, State of California, have 5 made and invented certain new and useful Improvements in Brick-Kilns; and I do hereby declare that the following is a full, clear, and exact description of the same, reference being had to the accompanying drawings.

10 My invention relates to improvements in brick-kilns for continuous burning. As now constructed, these kilns are composed of a number of separate compartments or chambers, from each one of which the bricks can be 15 drawn independently of the others as soon as its charge is properly burned.

My improvements, as hereinafter more particularly described, consist in a means of handling and conducting the heat, vapors, and 20 other products of combustion from one chamber into any one or several of the other chambers, as required, whereby in cooling off I am enabled to draw off the steam and heated gases from one chamber into any other chamber, to 25 utilize, instead of allowing these products to pass off and run to waste through the chimney. By means of these improved constructions and arrangement of flues, furnaces, and dampers, any one of the chambers can be cut out from 30 the others of the series and its contents cooled and drawn off without interfering with the operation of the others. The steam and vapors from one chamber can be conducted also into any other one of the series at will.

35 The following description fully explains the manner in which I proceed to construct, apply, use, and operate my invention, the accompanying drawings being referred to by letters and figures—that is to say:

40 Figure 1 is a perspective view of a kiln constructed according to my invention, a portion of the side wall and floor being broken away to expose the interior. Fig. 2 is a transverse vertical section through the center of two opposing chambers and the common flue. Fig. 45 3 is a vertical section taken longitudinally through one of the fire-places or furnaces in the chamber. Figs. 4, 5, 6 are details of the dampers for controlling the different flues and 50 passages.

In my improved construction of kiln each chamber has its own furnace. These are shown at B B' B² B³ B⁴ B⁵, &c., Fig. 1, and the chambers with which they are connected are seen at A A' A² A³, &c. Two sets of chambers are 55 arranged on both sides of a common flue, G, and each chamber is connected with it through an outlet, g, controlled by a valve, h. The furnaces B B', &c., are built on top of the kiln and communicate with the interior of the 60 chamber through passage I, leading downward back of the bridge-wall j. The course of the heat and products from the fire is down through the inlet I into the burning-chambers A A', &c., and out through the discharge- 65 opening g into the flue. The valves or dampers h are operated on the top of the kiln by means of rods H, as shown. In the bottom of each chamber there is formed an open flue, K. These are connected together by branch 70 passages L L', that lead from open pits m, located outside the side walls, and form the communication of the flues with these pits. Every two chambers A A', &c., are thus connected by the line of open flues K, passages L, and pits m. The end chamber A' 75 of one row of series is connected with the chamber A, or the first of the series on the other side, through the flue N, the passage P, and the pit m'. The tops of these pits are 80 open, and when in operation they are closed by covers and luted with clay. They are also fitted with cut-off plates or dampers R, Fig. 6, which are provided to slide into the pit and cut off communication between the passage L 85 L', leading from one chamber, and the corresponding passage leading from the other side of the pit to the next chamber. When all are placed in position, they shut off connection of each chamber with the adjoining one. They 90 are constructed of a metal plate, R, having projections r to receive and hold a coating of clay to protect it from heat, and a handle, r', for placing and drawing it out of the pits. By drawing out one of these plates and closing the pit with a cover, one chamber can be 95 put into communication with the adjoining one. In a similar manner I provide connecting-flues at the top of the chambers throughout the entire number; but in this construc- 100

tion I arrange for leading off the heat and vapor from any one or more chambers, and delivering these products into any particular chamber whether near to or distant from such discharging-chamber. This consists of a main flue, S, carried along in the top of the kiln—one to each series—with short independent flues T at each chamber leading out through the top or roof and opening into the chamber. 5 The arrangement of these flues is plainly shown in Fig. 1, where the tops of several chambers are seen in section. The outlets t of these flues are closed by plates properly luted or sealed, excepting where it is required to bring 10 one chamber in connection with the discharge-flue S. For this purpose a cover or damper, V, of novel form is provided, the construction and application of which are seen in Figs. 2, 4, and 5. It is made of suitable size to fit into 15 the channel or depression m' in the roof and around the outlet t', and it is provided with a central partition, v', and cut-off plates or partitions w w on one side, and a single plate, x, on the opposite side. It is used in one position or the other, according to the service 20 required of it. When this cover V is placed over this outlet, with the double partitions w w turned down, the outlets will be closed and cut off one from the other, and nothing can 25 pass through the flues; but by reversing the cover V the other side will bring either of the outlets t into connection with the mouth of the flue S, according to the way in which the cover is set, whether with the partition x to 30 the right or to the left. In this last position the partition rests on the dividing-ledge between the apertures S t, and the inclosed space in the cover forms the connecting-passage between the two flues S t. There are two of the 35 flues t in each chamber, one leading from the interior space, A, and the other from the damper-pit m' to the outlet, back to the furnace, and thus by means of these two flues the heat and gases from the chamber can be conducted into another chamber, or they can be 40 directed into the furnace to increase the combustion. The interior of one chamber can be connected with any one of the other chambers by simply fixing these covers V in the required 45 position over the apertures S t. In like manner the vapors of several chambers can be directed into the central flue, S, and so carried 50 along to any other chamber of the series. This arrangement of the flues at one side of the kiln 55 is the counterpart of those at the other side.

In constructing such a kiln I make the chambers A A' of separate arched compartments, with the arches running transversely, as in Figs. 1 and 2; or I form a continuous arched 60 roof, and then divide the space into chambers by walls, transverse walls, or partitions. The general arrangement of the chimney-flue G and the other flues and conduits is the same in both constructions. The furnaces, however, 65 are placed along the roof, with their fronts toward the center in the last-mentioned con-

struction, so that the two rows face each other, and the ash-pits extend in a continuous line over along the top of the chimney-flue G. In the other construction, Figs. 2, 3, a separate 70 ash-pit is provided to each furnace front.

The general operation of my improved kiln will be as follows: A number of the chambers being filled with brick or other material to be baked, the doors a a are closed and sealed. 75 The damper-plates R are placed in the pits m and sealed. Fire is then started—say at the first furnace A—and the chamber being connected with the chimney-flue G, by raising the damper h, the steam is carried off from the 80 drying material into the chimney. When the material in the first chamber is sufficiently dried, the damper h is closed and the damper of the next chamber is opened at the same time; also the plate R, separating the flues between the two chambers, is raised and the pit sealed by the covering-plate. The draft of 85 the first chamber is then taken through the second one, so that while the material in the first chamber is being raised to the required 90 temperature its heat is utilized to dry the material in the second chamber. As soon as the operation of burning is finished in two or more chambers, their flues t are connected with the main flue S by means of the covers, and the 95 flue S is then connected with the flue t of another chamber containing unburnt material; or the vapors and gases are directed into the furnace through the flue t' to assist the combustion in the furnace. The finished chambers thus cooling off into the unfinished ones assist in drying the material therein. This operation is repeated as each chamber is finished, and when a number are obtained the first one is opened, and after its contents are 105 removed it is charged again. In this manner the operation is made continuous, and the heat from the furnace is economically and effectively utilized and distributed.

Having thus fully described my invention, 110 what I claim, and desire to secure by Letters Patent, is—

1. In a burning-kiln, the chambers A A', &c., each pair being connected with a separate furnace, a common chimney-flue, G, outlets g, 115 for the chambers, and valves or dampers h, and connections beneath the chamber with means for controlling them, as set forth.

2. In a burning-kiln, the combination, with a series of burning-chambers, of a principal 120 outlet flue or conduit, S, flues t t' at each chamber, and a removable cap or cover, as V, provided with division-plates for separating or connecting said flues and conduit, as desired, substantially as set forth.

3. The combination, with the burning-chambers A A', of the flues K, damper-pits m, connecting-passages L L', and removable dampers R, provided with means for holding a coating of clay on each side, substantially as set 125 forth.

4. In a kiln for burning brick and other ma-

terial, a burning-chamber, as A, having flue *g*, leading to the chimney, and a furnace, as B, on top, and communicating with the interior of the chamber through a flue, as *I*, substantially as set forth.

5. The combination, with the conduit *S* and flues *t t'*, of cover *V*, provided with center plate, *v*, and a division-plate, *x*, on one side and two division-plates, *w w*, on the other, substantially as set forth.

6. The combination of the flues for connecting the chambers at the bottoms of the damper or stopper *R*, provided with the curved wings *r r* on the sides, to hold a coating of clay, as set forth.
